UNITED STATES PATENT OFFICE.

CHESTER WATERS LARNER, OF PHILADELPHIA, PENNSYLVANIA.

CENTRIFUGAL PUMP.

932,297.

Specification of Letters Patent. Patented Aug. 24, 1909.

Application filed August 9, 1905. Serial No. 273,366.

To all whom it may concern:

Be it known that I, CHESTER WATERS LARNER, a citizen of the United States, and resident of the city of Philadelphia, in the county of Philadelphia and State of Pennsylvania, have invented certain new and useful Improvements in Centrifugal Pumps, of which the following is a specification.

Objects of the present invention are to provide a simple, efficient and reliable balanced multiple stage centrifugal pump; to avoid end thrust and attain high efficiency; to obviate tortuous passages and to provide large open passages having easy bends; and to provide for obtaining the pressure or pressures corresponding to the different stage or stages.

To these and other ends hereinafter set forth the invention stated in general terms comprises the improvements to be presently described and finally claimed.

The nature, characteristic features and scope of the invention will be more fully understood from the following description taken in connection with the accompanying drawings forming part hereof and in which—

Figure 1, is a view principally in central section illustrating a pump embodying features of the invention. Fig. 2, is an end view of the same, and Fig. 3, is an end view of part 28.

In the drawings 1, is a shaft mounted so as to be revolvable in bearings 2 and 3 and shown as provided with a coupling 4 for rotating it, although of course it may be rotated in a variety of ways.

5, 6, and 7 represent each two stages and are duplicates of each other so that a description of one will suffice for all.

8, is the casing which is shown as arranged upon I-beams 9.

The impellers 10 and 11 are arranged back to back and are shown as provided with the usual webs or vanes. It will be observed upon reference to Fig. 1, that the casing is so arranged as to separate or isolate the impellers 10 and 11. This arrangement insures the absence of end thrusts on the shaft 1, since it constitutes what may be called a balanced structure in respect to the water pressure, the thrust on one impeller being offset by the equal but opposite thrust on the other. Within the casing there is an annular water way 12 of U-shaped cross-section leading through the usual diffusion

vanes 29 and extending from the outlet of the impeller 10 to the inlet of the impeller 11. This water way 12 is shown as provided with ribs to connect the opposite walls of the passage. 14, is a second annular water way also of U-shaped cross-section and arranged within the first mentioned water way 12 and in position generally similar to it. This water way 14 leads from the outlet of the impeller 11 through its set of diffusion vanes 30 and it communicates with channels 15 that extend across the water way 12 and communicate with a chamber 16 that leads to the inlet of the duplicate set of apparatus which constitutes the next stage 6.

17, is the intake and 18 is the outlet.

19, 20, 21 and 22 are auxiliary intakes of which those marked 19 and 21 communicate respectively with the U-shape water ways 12 of the parts 5 and 6, and of which those marked 20 and 22 communicate respectively with the chambers 16 that appertain to the parts 5 and 6. The pump shown has six stages and when the intakes 19, 20, 21 and 22 are closed fluid is delivered at 18 under pressure corresponding with the six stages. However, by using the other intakes progressively it is possible to obtain fluid at 18 at a pressure corresponding to the intake that is open.

As shown the shaft 1 is of largest diameter at its left-hand end and use is made of sleeves 23 which in connection with the jam nuts 24 serve to hold the impellers against end-wise motion and in proper place on the shaft; it being understood that the parts are assembled from right to left. The parts or castings 25 and 28 are separate from the castings 26 and these castings may be readily assembled and separated by means of the bolts 27.

In use the fluid enters at 17, is operated upon by the first of the impellers and reaches the water way 12 which by reason of its shape permits of the easy passage of the fluid and delivers it in the direction indicated by the arrows *a* to the second impeller. The latter delivers it through the water way 14 and channels 15 as indicated by the arrows *b* and by reason of the shape of the water way 14 and channels 15 the passage of the fluid is comparatively unobstructed. From the chamber 16 the fluid reaches the next set of apparatus or stage of the pump and the described operation is repeated until finally the fluid escapes at 18.

It will be obvious to those skilled in the art to which the invention relates that modifications may be made in details without departing from the spirit thereof, hence the invention is not limited further than the prior state of the art may require, but

Having thus described the nature and objects of my invention what I claim as new and desire to secure by Letters Patent is:

- 10 1. A pump having a casing and impellers arranged back to back and having an annular waterway from the outlet of the first impeller to the inlet of the second impeller, said waterway having a cross section of generally helical form in a plane which contains the axis of the pump, and a waterway from the outlet of the second impeller consisting of tubular channels crossing the first mentioned waterway, substantially as specified.
- 15 2. A balanced multiple stage centrifugal pump provided with impellers arranged back to back in pairs and with a casing having an annular waterway from the outlet 25 of the first impeller to the inlet of the second impeller, said waterway having a cross section of generally helical form in a plane which contains the axis of the pump, and a

second waterway of large area and easy bends beginning within the first waterway 30 and crossing it through tubular channels and connecting the second impeller of one pair with the first impeller of the next pair, substantially as specified.

3. A multiple stage centrifugal pump provided with impellers arranged back to back in pairs, a casing which separates the impellers whereby there is insured a maximum of balance and absence of end thrust, said casing having an annular waterway from 40 the outlet of the first impeller to the inlet of the second impeller, said waterway having a cross-section of generally helical form in a plane which contains the axis of the pump, and a second waterway consisting of 45 tubular channels crossing the first mentioned waterway and connecting the outlet of the second impeller with the inlet of the first impeller of the next pair, substantially as specified.

In testimony whereof I have hereunto signed my name.

CHESTER WATERS LARNER.

In the presence of—

W. J. JACKSON,
FRANK E. FRENCH.
